Patented June 7, 1960

188,150

TAPE DISPENSER

Irving J. Gershen, 1 Norwood Road, Springfield, N.J.

Filed Jan. 26, 1960, Ser. No. 59,175

Term of patent 14 years

(Cl. D74—1)

Fig. 1 is a front perspective view of a tape dispenser showing my new design;

Fig. 2 is an end elevational view looking at the right of Fig. 3;

Fig. 3 is an elevational view of the side shown in Fig. 1;

Fig. 4 is a top plan view thereof;

Fig. 5 is a bottom plan view thereof;

Fig. 6 is an end elevational view as seen from the left of Fig. 3;

Fig. 7 is an elevational view of the side opposite to that of Fig. 1 as it appears with the bridge in open position; and

Fig. 8 is an end elevational view thereof as seen from the right of Fig. 7.

I claim:

The ornamental design for a tape dispenser, substantially as shown.
